UNITED STATES PATENT OFFICE

126,226

DESIGN FOR A LAUNDRY TUB

Joseph C. Steiner, Chicago, Ill.

Application July 15, 1940, Serial No. 93,660

Term of patent 7 years

To all whom it may concern:

Be it known that I, Joseph C. Steiner, a citizen of the United States, residing at Chicago, Cook County, Illinois, have invented a new, original, and ornamental Design for a Laundry Tub, of which the following is a specification, reference being had to the accompanying drawing forming a part thereof, and in which

Fig. 1 is a front perspective view of a laundry tub showing my new design; and

Fig. 2 a rear perspective view thereof.

The characteristic features of the design reside in the laundry tub disclosed having the upper rear or bracket portions thereof of the specific configuration shown.

I claim:

The ornamental design for a laundry tub, as shown and described.

JOSEPH C. STEINER.
